(57) **CLAIM**

The ornamental design for a wheel and tire, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a front view of a wheel and tire showing the new design;

FIG. 1.2 is a back view thereof;

FIG. 1.3 is a left view thereof;

FIG. 1.4 is a right view thereof;

FIG. 1.5 is a top view thereof; and

FIG. 1.6 is a bottom view thereof.

The portion of the design shown in the color red is for the purpose of illustrating portions of the wheel that forms no part of the claimed design.
